(57) CLAIM

The ornamental design for sports headware, as shown and described.

DESCRIPTION

FIG. 1 is a front side view of sports headware showing my new design;

FIG. 2 is a right side view thereof;

FIG. 3 is a left side view thereof;

FIG. 4 is a rear side view thereof;

FIG. 5 is a top plan view thereof; and,

FIG. 6 is a front and left-side perspective view thereof, the face shown in broken lines forms no part of the claimed design.

The crossed pattern shown in broken lines in the two details in FIGS. 2, 3 and 6 forms no part of the claimed design.
